METALLURGICAL FURNACE OF THE
SUSPENDED ARCH TYPEKarl A. Lindner, Roselle Park, N. J., assignor to
American Smelting and Refining Company,
New York, N. Y., a corporation of New Jersey

Application May 31, 1933, Serial No. 673,674

12 Claims.

(Cl. 263—46)

This invention relates to metallurgical furnaces of the suspended arch type and particularly concerns improvements in the side wall construction of such furnaces.

5 Prior to the introduction of furnaces of the suspended arch type, which type shall be understood in the present specification and claims to designate furnaces in which the roof or arch is supported independently of the side wall, it was usual in the metallurgical art to employ 10 furnaces of the so-called sprung arch type in which the arch or roof sprung from the side walls and was supported thereby. Certain defects were, however, inherent in the construction 15 of furnaces of the sprung arch type. For example, the choice of materials for building the side walls was limited to relatively strong materials as the side walls supported the entire weight of the roof. In order to decrease damage to the 20 side walls, attempts were often made to employ lighter materials in the construction of the roof arch, but, while such construction decreased failures in the side walls, failures in the arches increased. These and other disadvantages attending the sprung arch construction led to the 25 development of furnaces of the suspended arch type.

With the advent of furnaces in which the roof was independently supported of the side walls, 30 many of the disadvantages accompanying the old sprung arch construction were eliminated. By independently suspending the roof and thus removing the load from the side walls, the range 35 of materials used in both side wall and roof construction was widened and many of the failures common in the sprung arch construction were eliminated.

However, furnaces of the suspended arch type when employed for the treatment of metals of a 40 high specific gravity, as, for example, lead or alloys thereof, have not been entirely satisfactory due to recurring failures of the side walls. In fact, side wall failures in the case of furnaces operating on such materials occur so frequently 45 that the use of suspended arch furnaces has often been abandoned in spite of the many other desirable features attending such construction. I have found that the repeated side wall failures in metallurgical furnaces of the suspended arch 50 type are due to vertical movement of the side walls themselves. In other words, the side walls of such furnaces especially when operating on metals having a high specific gravity and a low melting point tend to work upwardly with the 55 result that the metal enters the space formed within the refractory material comprising the side walls and causes the wall to fail.

By my invention it is possible to greatly reduce or practically eliminate failures of the side 60 walls in metallurgical furnaces employing the

suspended arch type of construction. To accomplish this desired objective I anchor the side walls at a point above the metal or bath line of the furnace in such manner that vertical movement of the refractory material comprising the 5 side walls is prevented.

Although the novel features which are believed to be characteristic of this invention will be particularly pointed out in the claims appended hereto, the invention itself, as to its objects and 10 advantages, and the manner in which it may be carried out, may be better understood by referring to the following description taken in connection with the accompanying drawing forming 15 a part thereof, in which

Fig. 1 is a cross-sectional view of a reverberatory furnace of the suspended arch type embodying the principles of the present invention;

Fig. 2 is a section of the side plate of the furnace of Fig. 1 showing one type of means suitable for practising the invention; and

Fig. 3 is a section taken along the line 3—3 of Fig. 2.

Like reference characters denote like parts in 25 the several figures of the drawing.

In the following description and in the claims, 30 various details will be identified by specific names for convenience, but they are intended to be as generic in their application as the art will permit.

Referring now to the drawing, a reverberatory furnace is shown with buckstays 9, refractory side walls 10 and roof 11 suspended by hangers 12. Brackets 13 affixed to side plates 14 project into and are embedded in refractory wall 10. 35 Walls 14a provide a water jacket extending to substantially the height of the metal or bath line 15, while 16 indicates the space in the jacket for the circulation of water.

In operation, the brackets 13 affixed as by 40 welding to the side plates 14 which in turn are secured to buckstays 9 in the same or a similar manner serve to anchor the refractory material comprising the side walls and resist upward vertical movement of the side walls when the furnace is in use. By thus inhibiting the upward vertical movement of the refractory walls the molten metal in the furnace is unable to penetrate the walls with the result that side wall 45 failures, not uncommonly experienced in suspended arch furnaces, are largely eliminated. While in the specific embodiment of the invention shown in the accompanying drawing vertical movement of the side walls is prevented by means of brackets welded to the side plates and embedded in the refractory walls above the metal line of the bath, other means of inhibiting the vertical movement referred to may be employed. For example, brazed beams extending along the 55 top of the refractory side walls and suitably an-

60

chored may be used. Again, other types of anchoring means suitably affixed to the side plates which will inhibit vertical side wall movement will be apparent to those skilled in the art.

5 It will thus be appreciated that the present invention by greatly reducing the number of side wall failures and eliminating the cause thereof makes possible the commercial use of metallurgical furnaces having independently supported 10 roofs in treating metals possessing high specific gravities, as, for example, lead and alloys thereof.

While certain novel features of the invention have been disclosed and are pointed out in the annexed claims, it will be understood that various 15 omissions, substitutions and changes may be made by those skilled in the art without departing from the spirit of the invention.

What is claimed is:

1. In a metallurgical furnace of the suspended 20 arch type, means for anchoring the refractory side walls of said furnace whereby vertical movement and failure of said side walls is prevented, said means comprising anchoring devices bearing downwardly on said side walls.

25 2. In a reverberatory furnace of the suspended arch type for treating lead or alloys thereof the combination comprising refractory walls, buckstays, side plates secured thereto and adjacent said walls and brackets affixed to said side plates 30 and embedded in said walls whereby vertical movement of said refractory walls is prevented.

3. In a metallurgical furnace of the suspended arch type for treating metals of high specific 35 gravity, vertical side walls formed of blocks of refractory material, said side walls being in direct contact with the molten metal below the metal line in said furnace and extending above said metal line, metal side plates covering the outside of said side walls and secured to an outer 40 retaining framework, and brackets secured to the inside surfaces of said side plates and embedded in said side walls to prevent vertical movement of said walls.

4. In a metallurgical furnace of the suspended 45 arch type, vertical side walls and a separately suspended roof of refractory material, said side walls extending from below the metal line of said furnace to said roof, an outer retaining member and brackets secured thereto and embedded in 50 said side walls intermediate said roof and said metal line to retain the lower portions of said walls in place.

5. In a metallurgical furnace of the suspended 55 arch type for treating metals of high density, vertical side walls of refractory material, a roof, said side walls extending from below the metal line in said furnace to said roof, a metal framework outside said furnace supporting said roof, and brackets secured to said framework and embedded in said side walls intermediate said roof and the metal line of said furnace to prevent vertical displacement of the lower portions of 60 said side walls.

6. A metallurgical furnace comprising the 65 combination with a framework and a roof suspended from the framework, of side walls cooperating with the roof but independent thereof, a reinforcing frame adjacent to the side walls, and brackets embedded in the side walls and rigidly 70 secured to the said reinforcing frame for overcoming tendency of the side walls to move under

the action of molten metal entering into openings in the side walls formed during operation of the furnace.

7. A metallurgical furnace comprising the combination with a framework and a roof suspended from the framework, of side walls cooperating with the roof but independent thereof, a reinforcing frame for the side walls including buckstays adjacent to the side walls and brackets embedded in the side walls and welded to the buckstays, the said brackets including bracing webs rigidly reinforcing the brackets, the said brackets and webs being adapted to overcome movement of the side walls under the action of molten metal entering into openings in the side walls formed during 10 operation of the furnace.

8. A metallurgical furnace comprising the combination with a framework and a roof suspended from the framework, of side walls cooperating with the roof but independent thereof, a reinforcing frame for the side walls including buckstays adjacent to the side walls and substantially triangular brackets embedded in the side walls and welded to the buckstays, the said brackets having one side extending at substantially right 20 angles to the buckstays and having their longest side positioned to rigidly brace the outstanding side for counteracting tendency of the side walls to become displaced under action of molten metal entering openings in the said walls formed during 30 operation of the furnace.

9. A metallurgical furnace comprising the combination with a framework and a roof suspended from the framework, of side walls cooperating with the roof but independent thereof, a reinforcing framework adjacent to the side walls, and means rigidly secured to the framework and embedded in the side walls in position to counteract 35 tendency of the side walls to become displaced under action of molten metal entering openings 40 in the said walls.

10. A metallurgical furnace comprising the combination with a framework and a roof suspended from the framework, of side walls cooperating with the roof but independent thereof, a reinforcing framework adjacent to the side walls, and means secured to the framework and associated with the side walls in position to counteract 45 tendency of the side walls to become displaced under buoyant action of molten metal entering 50 openings in the side walls.

11. A metallurgical furnace comprising the combination with a framework, of a roof suspended from the framework, an outer retaining framework, side plates secured thereto, brackets 55 integral therewith, and refractory side walls, the said brackets being anchored in the said refractory side walls at a point above the metal line of the furnace and acting upon the side walls to counteract any tendency of the side walls to become displaced through buoyant action of molten metal entering openings in the side walls.

12. A metallurgical furnace comprising, in combination, a suspended roof, refractory walls and anchored side plates with brackets secured thereto, the said brackets being embedded in the 65 said refractory walls and bearing thereon to resist tendency of deformation of the walls under buoyancy of molten metal entering openings in 70 the said walls.
